Allan Ramsey, Evanston, Ill., assignor to
Schweitzer & Conrad, Inc., Chicago, Ill., a
corporation of Delaware

Application December 14, 1936, Serial No. 115,693

18 Claims. (Cl. 200—48)

My invention relates, generally, to electric switches, and it has particular relation to disconnecting switches for electric power transmission lines.

It is customary to provide disconnecting switches in electric power transmission lines for the purpose of sectionalizing them or for the purpose of disconnecting a feeder circuit from the line. Ordinarily such switches are of the air break type, and they are mounted out of doors on one of the transmission line poles or towers. In the construction of such a switch, care must be taken to provide a suitable electrical clearance between the relatively movable switch members when they are in the open position in order to prevent flashover.

For this purpose various types of disconnecting switches have been provided. One of these types comprises a pair of pillar type insulators, one of which is stationarily mounted and carries a contact assembly that is connected to one of the line conductors, the other being mounted for rotation in the plane of its axis and carrying a switch arm that is movable into and out of contact engagement with the contact members carried by the other insulator. The switch arm is electrically connected to the other line conductor. It is to improvements in the construction of this type of switch that my invention is directed.

It has been the practice in the past to employ flexible shunt connectors between the movable switch arm and the line conductor associated therewith. These shunts deteriorate when exposed to the weather, and require periodic replacement.

Another difficulty that has been encountered in this type of switch lies in the requirement of accurate alignment of the relatively movable switch members, constructed in accordance with the teaching of the prior art, which calls for a high degree of accuracy in the installation of the switch and frequent inspections and adjustments to maintain the accurate alignment. The problem becomes particularly acute when two or more disconnecting switches are mounted for simultaneous operation by a single operating mechanism. These difficulties will be more readily appreciated when it is recalled that the complete insulator and associated switch arm are moved to open or close the switch. The insulator is ordinarily relatively heavy, and with the switch arm mounted on one end it presents an unwieldy mechanism to be moved with any degree of accuracy.

When only the two insulators are employed, one for the stationary switch member and one for the switch arm, difficulty is encountered in connecting the switch arm to its associated line conductor unless careful alignment is maintained between the switch and the conductor. The difficulty is increased when a direct connection is provided by relatively inflexible connectors. It is often not possible to provide the desired alignment between the line conductor and the switch, and, even if it is provided, the line conductor will sway because of the effects of the wind or vibrations that may be set up therein. Unless provision is made for taking care of this misalignment, the necessary movement of the switch arm to properly engage the stationary contact member will be interfered with.

An important object of the present invention is to provide a disconnecting switch for transmission line conductors in which a highly accurate alignment of the relatively movable switch members is not required.

Another important object of my invention is to incorporate in a transmission line disconnecting switch individually flexible and resilient pre-stressed contact fingers, each of which has a small area high pressure contact engaging surface for contact engagement with a relatively movable switch member having like contact surfaces which do not require accurate positioning either to make or maintain efficient contact engagement therebetween.

Still another important object of my invention is to provide for connecting the movable switch arm of a disconnecting switch directly to a line conductor by an inflexible connecting link in such manner as not to interfere with its operation despite a limited movement of the line conductor.

An object of my invention is to provide a simple means for connecting a common operating member to the movable insulator of each of several poles of transmission line disconnecting switches to permit simultaneous operation of all of the poles.

Another object of my invention is to provide an improved base for a transmission line disconnecting switch to which the strain insulators supporting the line conductors may be directly fastened.

A further object of my invention is to provide silver contact engaging surfaces between the relatively movable switch members of a disconnecting switch.

A still further object of my invention is to in-

crease the resistance to torsional stress of a light section sheet metal operating shaft used for simultaneously operating two or more poles of a disconnecting switch.

5 Other objects of my invention will, in part, be obvious and in part appear hereinafter.

My invention, accordingly, is disclosed in the embodiments hereof shown in the accompanying drawings, and it comprises the features of construction, combination of elements, and arrangement of parts which will be exemplified in the constructions hereinafter set forth, and the scope of the application of which will be indicated in the appended claims.

15 For a more complete understanding of the nature and scope of my invention, references may be had to the following detailed description taken in connection with the accompanying drawings, in which:

20 Figure 1 is a view, in side elevation, of a transmission line disconnecting switch constructed in accordance with the present invention;

25 Figure 2 is a view, in top plan, of the bases for two transmission line disconnecting switches arranged for simultaneous operation, the switches themselves being omitted;

Figure 3 is a detail sectional view taken along the line 3—3 of Figure 2;

30 Figure 4 is a detail sectional view taken along the line 4—4 of Figure 3;

Figure 5 is a detail sectional view taken along the line 5—5 of Figure 2;

Figure 6 is a view, similar to Figure 5, and showing a different type of operating shaft;

35 Figure 7 is a view at an enlarged scale, partly in side elevation and partly in section, showing the arrangement and construction of the switch members shown in Figure 1;

Figure 8 is a view, in top plan, of the switch members shown in Figure 7, the sleet hood being omitted;

Figure 9 is a detail sectional view taken along the line 9—9 of Figure 7;

45 Figure 10 is a detail sectional view taken along the line 10—10 of Figure 7;

Figure 11 is a perspective view of the line connector to which the switch arm is connected, and showing the construction of one of the universal joints;

50 Figure 12 is a perspective view of another of the universal joints;

Figure 13 is a view, in side elevation, of a modified form of the disconnecting switch in which three, in place of two, insulators are employed;

Figure 14 is a view, similar to that shown in Figure 9, illustrating a modified form of contact construction;

Figure 15 is a view, in top plan, of an improved 60 form of operating shaft; and

Figure 16 is an end view of the operating shaft shown in Figure 15.

Referring particularly to Figures 1 and 2 of the drawings, it will be observed that the reference character 15 designates, generally, a two-poled disconnecting switch for opening the circuit in the two conductors of a two wire transmission line. It will be understood that only a single pole unit may be employed, or that three or four poles may be employed, as required, without departing from the scope of my invention.

Each pole of the switch 15 is provided with a switch base, shown generally at 16, that may be mounted on cross arms 17 which may be secured 75 to the upper end of a pole 18. Each switch base

16 comprises a pair of frame members 19 in the form of angles having suitable apertures in the lower flanges to permit mounting on the cross arms 17 that may be variably spaced. An L-shaped bracket 20 is welded between the left-hand ends of the frame members 19, and an insulator support bracket 21 is welded between the right hand ends, as illustrated. The outwardly extending ends of the brackets 20 and 21 are provided with transverse apertures to permit connection thereto of strain insulators 22 and 23 to which line conductors 24 and 25 are fastened. Generally, the conductors 25 will be normally energized, and conductors 24 will be energized only when the switch 15 is in the closed position.

The insulator support bracket 21 is provided with an inclined intermediate section 29 on which may be bolted a pillar type insulator 30. Stationarily mounted on the upper end of the insulator 30 is a contact assembly, shown generally at 31, the details of construction of which will be illustrated and described hereinafter. A conductor 32 is provided for electrically interconnecting the switch member 31 and the line conductor 25.

Rotatably mounted intermediate the ends of the switch base 16 is a yoke, shown generally at 33, that is generally rectangular in shape and on which is mounted a pillar type insulator 34. At its upper end the insulator 34 carries a switch arm support bracket 35 for rotatably mounting a switch arm, designated generally by the reference character 36. A guide member 37, wedge-shaped at its upper end, is carried by the support bracket 35 to guide the switch arm in its movement relative thereto.

A link, shown generally at 37a, is provided for interconnecting the switch arm 36 and a line clamp 38, both electrically and mechanically. Universal joints, shown generally at 39 and 40, are provided at each end of the link 37a for furnishing the required mechanical and electrical connection with the switch arm 36 and line clamp 38. The left hand end of the bracket 35 is turned upwardly to provide a stop for the switch blade 36 to insure that the line clamp 38 will not be positioned too far away from the switch 15 on installation. In this manner proper alignment of the switch blade 36 with the contact assembly 31 will be assured. The details of construction of the universal joints 39 and 40 will be set forth hereinafter. Arcing horns 41 and 42 are carried by the support bracket 35 and the switch member 31, respectively, to cause the arc to be formed therebetween when the switch 15 is opened under load.

With a view to mechanically interconnecting the rectangular yokes 33 to permit simultaneous rotation of the insulators 34 and the switch arms 36 carried thereby, an operating shaft 44 in the form of a Z-shaped structural section is positioned therein and clamped by means that will be presently described. An operating lever 45 is secured to the connecting shaft 44, having at its outer end an operating rod 46 connected thereto. As shown, the operating rod 46 extends downwardly, and at its lower end it is pivotally mounted on a pin 47 carried by an arm 48 forming a part of a handle 49. The arm 48 is rotatably mounted on a suitable bracket 50 that may be fastened to the pole 18. When the handle 49 is rotated in the direction indicated by the broken line 51, the pin 47 moves in the path indicated by the broken line 52 to operate the switch 15 to the open position. The relative positions of the various movable parts of the switch 15 in the open

position are shown by the broken line outline thereof in Figure 1.

The construction of the rectangular yoke 33 is illustrated more clearly in Figures 3 and 4 of the drawings, to which reference will now be had. As there shown, the yoke 33 comprises a pair of interfitting generally U-shaped members 55 and 56 that may be bent to the desired shape from steel plate-like material. The member 55 may be secured, as by rivets 57, to a pair of bearing brackets 58 that are secured to a shaft 59, extending through suitable apertures in the frame members 19, by means of pins 60. One end 61 of the member 56 is bent outwardly to form a stop for movement of the switch to the open position by engagement with the upper edges of the frame members 19. The other end 62 of the member 56 serves as a stop for movement of the switch to the closed position by like engagement with the upper edges of the frame members 19.

The pin of the insulator 34 is secured to the yoke 33 by suitable cap screws 63 that are positioned in suitable threaded holes in the members 55 and 56.

With a view to securing the connecting shaft 44 in the yoke 33, a clamp plate 64 is provided within the rectangle formed by the members 55 and 56, and its ends are turned upwardly as shown in Figure 3. Set screws 65, that are threaded in suitable threaded holes in the members 55 and 56, bear against the upper surface of the clamp plate 64 and, when tightened, serve to fasten the connecting shaft 44 securely in place. It will be understood that the pin of the insulator 34 is provided with four clearance holes, only two of which are used by the cap screws 63 for holding it in position. The set screws 65 are positioned in the remaining two holes for the purpose of bearing against the clamp plate 64 as described.

The manner in which the operating lever 45 is fastened to the connecting shaft 44 is shown more clearly in Figure 5 of the drawings. It will be understood that the operating lever 45 is positioned suitably on the connecting shaft 44 intermediate the two switch bases 16 to properly align it with the pin 47 carried by the arm 48. Bolts 61, extending through suitable clearance holes in the operating lever 45 and in a plate 68 underneath the connecting shaft 44, serve to secure the operating lever 45 in position. Instead of employing the Z-shaped connecting member or shaft 44, it is also possible to employ a channel-shaped member or an I-shaped member therefor.

It may be undesirable to employ a metallic member for the connecting shaft 44 where it is required that the switch bases 16 be fully insulated from each other. For this purpose a wood connecting shaft 69 may be employed, as shown in Figure 6 of the drawings, instead of the metal connecting shaft 44 shown in Figure 5. Pointed projections 70 are provided underneath the operating lever 45, as illustrated, for penetrating the upper surface of the wood connecting shaft to more securely connect it thereto. It will now be apparent that metal or wood connecting shafts may be employed as desired, without requiring any special parts for either type of shaft.

The construction of the switch members mounted on top of the insulators 30 and 34 is more clearly illustrated in Figures 7, 8, 9 and 10, to which reference now will be had. It will be noted that the right hand end of the support bracket 35 is bifurcated and that the sections 12

thus formed are bent upwardly and given a ninety-degree twist through which a pin 73 may be positioned for rotatably supporting the switch blades 74 and 75 forming the switch arm 36. The guide member 37 carried by the upturned left hand end of the support bracket 35 interfits between the switch blades 74 and 75 to guide them into the switch closed position. The relationship of the guide member 37 to the switch blades 74 and 75 is shown more clearly in Figure 10. Since the switch blades 74 and 75 are relatively wide, are spaced relatively far apart, and are substantially braced together, they form a light weight and inflexible construction. The bearing points on the pin 73 and between the sections 72 are, therefore, widely spaced and insure accuracy of alignment with the contact assembly 31.

The switch blades 74 and 75 are provided, respectively, with flexible switch fingers 76 and 77 that may be suitably secured thereto as by the rivets illustrated and having the free ends curved as indicated at 78 and 79, Figure 9, to form convex contact surfaces for contact engagement with correspondingly shaped contact surfaces 80 and 81 of flexible contact fingers 82 and 83. The switch fingers 76 and 77 and the contact fingers 82 and 83 are formed preferably of strap copper, and they are subjected to forming dies to provide the desired shapes. The contact fingers 82 and 83 are mounted by means of bolts 84 which extend through a terminal block 85 composed preferably of copper. The lower ends of the contact fingers 82 and 83 have bosses 86 and 87 integrally formed therewith by a suitable upsetting operation for interfitting with recesses 88 and 89 in the block 85 to prevent them from turning about the bolts 84. The copper block 85 is mounted on a bracket 90 in the form of a copper strap which is bolted, as illustrated, to the upper end of the insulator 30.

With a view to providing a relatively high contact pressure between the curved ends 78 and 79 of the switch fingers 76 and 77 and the correspondingly shaped surfaces 80 and 81 of the contact fingers 82 and 83, compression springs 91 are interposed between the outer ends of the contact fingers 82 and 83, thereby serving to bias them apart. Stop members 92 in the form of rivets are loosely mounted in suitable apertures 93 near the ends of the contact fingers 82 and 83 for limiting the movement apart thereof under the influence of the compression springs 91. The distance between the headed ends of the rivets 92 is such as to permit a slight movement apart of the contact fingers 82 and 83 when the switch fingers 76 and 77 are moved out of contact engagement therewith. The contact surfaces 80 and 81 are then positioned slightly within the path of relative movement of the curved ends 78 and 79 of the switch fingers 76 and 77. It will then be apparent that it is only necessary to compress the springs 91 slightly when the switch is operated to the closed position to obtain the effect of its resiliency, this effect being the same as if the contact fingers 82 and 83 were moved from their relative positions which they would normally assume under the influence of the springs 91 if the stop member 92 were not present. Thus only a slight amount of work need be done in further compressing the springs 91 to obtain the full resilient effect thereof when the switch is closed. This construction provides what is now known as a prestressed contact finger construction, the principles of which are de-

scribed in my copending application, Serial No. 445,548, filed April 19, 1930, and assigned to the assignee of this application, now Patent No. 2,063,954 dated December 15, 1936. When the principle of prestressing is employed it is possible to provide a relatively high contact pressure between the mutually engaging contact surfaces of relatively movable switch members and, at the same time, provide a simple form of switch construction as illustrated herein. Tubular members 93 are positioned around the springs 91 to protect the latter and to improve the general appearance of the switch. A guide bracket 94 is mounted, as illustrated, on the block 85, and its upper end is bent into a horizontal position and tapered to guide the switch fingers 76 and 77 into proper engagement with contact fingers 82 and 83.

With a view to further increasing the contact pressure between the contact engaging surfaces, to increase the number of contact engaging surfaces and to generally improve the efficiency of the switch, a reenforcing member 96 is mounted on the upturned right hand end of the bracket 90 so that it extends horizontally in the plane of the switch arm 36 when it is in the closed position. The reenforcing member 96 is of substantially U-shape, is formed preferably of relatively thick strap copper, and it has a reenforcing member 97 in the form of a rivet extending therethrough, as illustrated, to prevent lateral displacement of the arms thereof. Rivets having spherical shaped heads 98 and 99 are secured near the outer ends of the switch fingers 76 and 77, and they are adapted to engage the inner surfaces of the arms of the U-shaped reenforcing member 96. The outer ends of the arms are flared outwardly in order to readily permit the movement of the rivet heads 98 and 99 into the switch closed position.

It will be observed that the curved ends 78 and 79 of the switch fingers 76 and 77 engage the correspondingly shaped surfaces 80 and 81 of the contact fingers 82 and 83 substantially at right angles. In this manner substantially point contact engagement takes place therebetween. In addition, a similar point contact engagement takes place between the rivet heads 98 and 99, which are preferably formed of copper, and the inner surfaces of the arms of the reenforcing member 96. In effect, then, there are six points at which contact engagement takes place in the particular embodiment of the switch disclosed herein. The combination of the action of the compression springs 91 and of the reinforcing member 96 insures that a relatively high contact pressure is available between the relatively movable switch members and, since the contact engagement therebetween takes place within relatively small areas, a high unit contact pressure is applied. Moreover, because of the individual flexibility and resiliency of the switch fingers 76 and 77 and of the contact fingers 82 and 83, contact engagement under substantial pressure is obtained at all six contact points.

Since the switch fingers 16 and 17 move transversely with respect to the contact fingers 82 and 83 from and to the switch closed position, any oxide coating or other film that might tend to increase the contact resistance is removed by the scraping action which ensues. The scraping action provides a clean contact surface, and the relatively high contact pressure insures that a minimum of heating will result at the contact surfaces.

A terminal bracket 100, in the form of an L-shaped strap, is secured to the bracket 90 and is provided with suitable apertures for connection of the conductor 32 (Figure 1), thereto.

It is desirable to protect the contact fingers 82 and 83 from the weather as much as possible, and for this purpose a sleet hood 101, formed preferably of sheet metal, is mounted on the bracket 90, as illustrated. The sleet hood 101 opens downwardly, and, since the switch arm 36 moves horizontally and downwardly when operated to the open position, it does not interfere with the functioning of the switch.

The particular manner in which the tiltable insulator 34 is rotatably mounted, together with the positioning of the switch blade 36 thereon, makes possible the provision of the sleet hood 101 in a position where it fully protects the contact assembly 31 from the weather. It will be observed that the insulator 34 is mounted in a vertical position when the switch 15 is closed. A line drawn through the centers of the shaft 59 and the pin 73 is inclined slightly from the vertical axis of the insulator 34. As soon as the handle 49 is operated to open the switch the pin 73 moves about the shaft 59 as an axis and initially moves upwardly. At the same time, because of the provision of the inflexible link 37a, the left-hand end of the switch blade 36 is elevated so that it rotates slightly about the pin 73 and the right-hand end is moved slightly downwardly at the same time that it is withdrawn from the contact assembly 31. The sleet hood 101 may then be of ample length to fully cover the contact assembly. At the same time, in the open position of the switch 15, as illustrated by the broken lines, the required electrical clearance distance is provided between the right-hand end of the switch blade 36 and the contact assembly 31. In this manner a compact and sturdy construction is provided in a minimum of space and with a minimum of cost and the parts that are likely to get out of adjustment are fully protected from the weather.

As indicated hereinbefore, it may not be practical or convenient to exactly align the line conductor 24 with the switch arm 36 that is electrically and mechanically connected thereto. Moreover, even if exact alignment is initially provided, the chances are that it will not remain, because of the swaying of the line conductor 24 in the wind, or because of slight movement of the pole 18 relative thereto. While it is desirable to provide a substantially rigid mechanical and electrical connection between the conductor 24 and the switch arm 36, the connection must be such that the movement of the conductor 24 out of its initial alignment will not affect the operation of the switch arm 36 in moving to and from the switch closed position. It is for this purpose that the link 37a, formed by a pair of copper straps 104 and 105, is provided, Figures 11 and 12, with the universal joints 39 and 40 at each end. The universal joint 39 comprises a rectangular block 107, preferably formed of copper, having a pin 108 extending through it and through the switch blades 74 and 75 of the switch arm 36. In like manner, a pin 109 also extends through the block 107 in a plane at right angles to that in which the pin 108 is positioned, and it extends through the straps 104 and 105 forming the link 37a. Spring washers 110 are positioned under the headed ends of the pins 108 and 109 in order to bias the switch blades 74 and 75 and the straps 104 and 105.

and 105 into contact engagement with the adjacent surfaces of the block 107 under considerable pressure. At the same time, the switch blades 74 and 75 and the straps 104 and 105 5 are permitted to rotate relative to the block 107 in planes at right angles to each other while still maintaining said contact engagement therewith. In like manner the other universal joint 40 comprises a block 111 through which extends a pin 10 112. The pin 112 also extends through the straps 104 and 105. A similar pin 113 extends through the upstanding arms of a U-shaped yoke 114 and through the block 111. Spring washers 115 are positioned underneath the headed ends of the 15 pins 112 and 113 to bias the straps 104 and 105 and the arms of the yoke 114 into contact engagement with the block 111. At its lower end, the yoke 114 is rotatably mounted by means of a rivet 116 on an integrally formed raised portion 20 117 of the upper section of the connector clamp 38. A spring washer 118 is positioned under one end of the rivet 116 and a similar washer is located under the other end beneath the raised portion 117 for securing the desired contact engagement under pressure.

It will now be apparent that the provision of the universal joints 39 and 40, constructed as just described, permits considerable latitude in the positioning of the conductor 24 with respect 30 to the switch arm 36 without interfering in the slightest with the satisfactory operation of the latter. Not only is this true, but also any swaying of the conductor 24 relative to the switch will not be translated to movement of the switch 35 arm 36.

In some installations it may be undesirable to connect the switch arm 36 directly to the conductor 34, the latter being mounted so that it may move relative to the switch arm. If it is desired 40 to stationarily position the end of the conductor 24 to which the switch arm 36 is to be connected, the switch construction shown generally at 120 in Figure 13 of the drawings may be employed. As there shown, in addition to the two insulators 45 30 and 34, a third insulator 121 is provided and mounted on a bracket 122 that is positioned between the frame members forming the switch base 123. The switch base 123 may be identical 50 in construction with that of the switch base 16 except that the frame members are slightly longer, and the bracket 122 is provided not only for supporting the insulator 121 but also for providing a support for the strain insulator 22.

A terminal member 124 is mounted on top of 55 the insulator 121 for connection thereto of the conductor 24. The terminal member 124 is electrically and mechanically connected to the left hand end of the switch arm 36 by a link 125 that may be formed of a pair of copper straps. 60 At its lower end the link 125 is mounted on a block 126 that is riveted on its underside to the terminal member 124. A pin 127 extends through the straps forming the link 125 and through the block 126. The ends of the pin 127 are headed 65 over, and spring washers 128 are positioned underneath (only one of which is shown) for biasing the straps forming the link 125 into contact engagement with the sides of the block 126. A cylindrical spacer 129, having a longitudinal aperture, is positioned between the upper ends of 70 the straps forming the link 125, and a pin 130 extends therethrough and through the straps. Spring washers 131 (only one of which is shown) are positioned under the headed ends of the pin 75 130 for biasing the blades forming the switch

arm 36 into contact engagement with the straps forming the link 125. If desired, suitable grease fittings 132 may be mounted on the block 126 and on the spacer 129 to permit greasing of the relatively movable parts located thereat.

Since the left hand end of the switch arm 36 is guided by the link 125 in a more substantial manner than it is guided in the switch construction shown in Figure 1 of the drawings, it is unnecessary to use the guide member 37 carried by the support bracket 35, and, therefore, it is omitted. The third insulator 121 provides this aligned support, and therefore it is unnecessary to utilize the universal joints 39 and 40 previously described. The wood connector shaft 69, 18 shown in Figure 6 of the drawings, may be employed in the yoke 33 for permitting simultaneous operation of two or more of the switches 120.

It will be understood that two or more poles constructed as illustrated in Figure 13 and described hereinbefore may be provided and simultaneously operated by a single operating mechanism. It will be understood that the mounting for such an assembly would be similar to that shown in Figure 2 of the drawings, and, since it 25 will be readily understood, it will not be described in detail herein.

In Figure 14 of the drawings I have illustrated a modified form of construction for the switch and contact fingers that are shown in Figure 9 30 of the drawings and described hereinbefore. As indicated in my copending application, Serial No. 115,694, filed December 14, 1936, and assigned to the assignee of this application, it is pointed out 35 that it is desirable to employ silver contact engaging surfaces for the relatively movable members of a switch in order to provide low resistance contact engaging surfaces that will not be appreciably affected or their characteristics changed throughout the life of the switch. In 40 Figure 14 of the drawings the manner in which the silver contact engaging surfaces may be applied to the transmission line disconnecting switch 15 is illustrated. As there shown, the switch fingers 18' and 19' are provided with silver 45 inserts 138 and 139, while the contact fingers 82' and 83' are provided with similar silver inserts 140 and 141. The manner in which the silver inserts are positioned in the switch and contact 50 fingers is described in my copending application, Serial No. 115,694, and, therefore, a detailed description thereof will not be set forth herein. Since the switch fingers 18' and 19' and the contact fingers 82' and 83' are relatively light, 55 it may be advisable, from a cost standpoint, to form them of copper strips or strap in which the silver inserts are positioned throughout the entire length thereof. The original stock for these members would be purchased in strips of indefinite length and the necessary lengths cut therefrom as required. The switch and contact fingers would then be upset and machined as required to provide the cylindrical contact engaging surfaces for providing substantially point contact engagement therebetween.

Since the silver inserts in the switch and contact fingers form parts of oppositely curved cylindrical surfaces that engage substantially at right angles, a point contact engagement therebetween 70 is provided over a wide range of relative positioning of the switch and contact fingers, either longitudinally or transversely. Therefore, it is unnecessary to provide a highly accurate operating mechanism which would cause the contact 75

engagement to take place at positions in which accurate alignment would be required.

With a view to providing silver contact engaging surfaces between the remaining contact points, the arms of the reinforcing member 96' are provided with silver inserts 146 that are formed preferably by a circular copper member overlaid with a layer of solid silver, as described in my copending application, Serial No. 115,694, hereinbefore referred to. The copper rivets 98' and 99' carried by the switch fingers 78' and 79' are drilled and countersunk for receiving silver rivets 148 to form the contact engaging surface with the inserts 146. It will be understood that the inserts 146 are large in diameter as compared to the rivets 148 for the purpose of securing the desired silver to silver contact without requiring an accurate positioning of the switch fingers 78' and 79'.
20 When the foregoing construction is employed, low resistance contact engaging surfaces will be provided at all six contact points. Moreover, the contact engagement will take place within small areas, approaching point contact, and because 25 of the individual flexibility and resiliency of the switch and contact fingers, each will carry its share of the current, with the result that no one of them will be overloaded.

When the individual units forming the switch 30 15 are spaced relatively far apart and the Z-shaped operating shaft 44 is employed, there is a tendency for it to twist since it is formed of relatively light sheet metal that has been bent to the shape indicated. In order to increase 35 the resistance of the operating shaft to torsional stress, the construction shown at 44' in Figures 15 and 16 of the drawings may be employed. For the purpose of increasing the resistance of the operating shaft 44' to torsional stress, a reinforcing member 150, in the form of a steel rod is formed into the shape indicated and welded at the points 151 where it engages the surface of the connecting shaft 44'. A reinforcing member 150 is provided on each side of the connecting shaft 44', 40 as shown in Figure 16. This construction provides a relatively simple and economical manner in which the light-weight operating shaft 44 may be braced. It is unnecessary to position the reinforcing members 150 with a high degree of accuracy and therefore this construction lends itself readily to manufacture and assembly. Ordinarily the connecting shaft 44' will be formed of $\frac{1}{8}$ " thick hot-rolled steel and shaped to a rectangular outline approximately 2" x 4". The 45 reinforcing members 150 may be of $\frac{1}{4}$ " steel rod material that is readily bent and welded as illustrated and described.

Since certain further changes may be made in the above constructions and different embodiments of the invention may be made without departing from the scope thereof, it is intended that all matter contained in the above description or shown in the accompanying drawings shall be interpreted as illustrative and not in a limiting 55 sense.

I claim as my invention:

1. A switch comprising, in combination, a pair of relatively movable switch members, a first pair of spaced apart flexible contact fingers carried by one of said switch members and each having a convex longitudinal contact surface, a second pair of spaced apart flexible contact fingers carried by the other of said switch members and each having a convex longitudinal contact 75 surface for individual contact engagement with

the corresponding contact surfaces of said first pair of contact fingers, and a pair of substantially inflexible contact fingers disposed adjacent one of said pairs of flexible contact fingers in such manner as to be engaged by the other of said pairs of flexible contact fingers when said contact engagement takes place. 5

2. A switch comprising, in combination, a pair of relatively movable switch members, a first pair of spaced apart flexible contact fingers carried by one of said switch members and each having a convex longitudinal contact surface, a second pair of spaced apart flexible contact fingers carried by the other of said switch members and each having a convex longitudinal contact 10 surface for individual contact engagement with the corresponding contact surfaces of said first pair of contact fingers, means biasing the contact fingers of one of said pairs of contact fingers relative to each other, means limiting the relative movement of said biased contact fingers to position their contact surfaces slightly within the path of relative movement with the contact surfaces of the other pair of contact fingers, and a pair of substantially inflexible contact fingers 15 disposed adjacent one of said pairs of flexible contact fingers in such manner as to be engaged by the other of said pairs of flexible contact fingers when said contact engagement takes place. 20

30

3. A switch comprising, in combination, a pair of relatively movable switch members, a first pair of spaced apart flexible contact fingers carried by one of said switch members and each having a convex longitudinal contact surface, a second pair of spaced apart flexible contact fingers carried by the other of said switch members and each having a convex longitudinal contact surface for individual contact engagement with the corresponding contact surfaces of said first 35 pair of contact fingers, means biasing the contact fingers of one of said pairs of contact fingers relative to each other, means limiting the relative movement of said biased contact fingers to position their contact surfaces slightly within the path of relative movement with the contact surfaces of the other pair of contact fingers, a pair of substantially inflexible contact fingers disposed adjacent one of said pairs of flexible contact fingers in such manner as to be engaged by the other of said pairs of flexible contact fingers when said contact engagement takes place, and a small radius projection carried by each of the flexible contact fingers engageable with said inflexible contact fingers and constituting the contact engaging portion therebetween. 45

4. In a switch for interconnecting a pair of high voltage transmission line conductors, in combination, a pair of spaced apart switch blades rotatably mounted intermediate the ends thereof, a first block of conducting material rotatably mounted between said switch blades at one end, a pair of spaced apart link members rotatably mounted at one end on said first block, a second block of conducting material rotatably mounted 60 between the other ends of said link members, a connector secured to one of said conductors, and a U-shaped member rotatably mounted on said connector and rotatably mounting said second block. 65

70

5. A base for a switch for interconnecting a pair of high voltage transmission line conductors comprising, in combination, a pair of spaced apart frame members, a first insulator support bracket secured between said frame members at 75

- one end and having an apertured portion extending therefrom for connection to a strain insulator to which one of said conductors is fastened, a second insulator support bracket rotatably mounted intermediate the ends of said frame members, and an apertured bracket secured between said frame members at the other end for connection to a strain insulator to which the other of said conductors is fastened.
- 5 10. A switch comprising, in combination, a pair of relatively movable switch members, a first pair of spaced apart flexible contact fingers carried by one of said switch members and each having a convex longitudinal contact surface, a second pair of spaced apart flexible contact fingers carried by the other of said switch members and each having a convex longitudinal contact surface for individual contact engagement with the corresponding contact surfaces of said first pair 15 of contact fingers, means biasing the contact fingers of one of said pairs of contact fingers relative to each other, means limiting the relative movement of said biased contact fingers to position their contact surfaces slightly within the 20 path of relative movement with the contact surfaces of the other pair of contact fingers, a pair of substantially inflexible contact fingers disposed adjacent one of said pairs of flexible contact fingers in such manner as to be engaged by the other of said pairs of flexible contact fingers when 25 said contact engagement takes place, and a small area contact engaging member interposed between each flexible contact finger and the corresponding inflexible contact finger and constituting the sole contact engaging portion therebetween.
7. A switch for interconnecting a pair of transmission line conductors likely to be positioned in varying degrees of misalignment comprising, in 30 combination, a stationary switch member for connection to one of said conductors, a rotatable support member, a switch arm rotatably mounted on said support member for movement into and out of contact engagement with said switch member, a connector clamp for mounting on the other conductor, an inflexible link electrically and mechanically interconnecting said clamp and said switch arm, and stop means carried by said support member limiting the position of said clamp 35 on said conductor to insure proper contact engagement between said switch arm and said switch member.
8. A light weight base for a disconnecting switch adapted to be mounted on a pole comprising, in combination, a pair of spaced apart structural frame members, a bracket formed of plate-like material and secured between said frame members at each end to rigidly brace them relative to each other, one of said brackets being arranged and adapted to support an insulator, and an insulator support bracket rotatably mounted between said frame members intermediate the ends thereof.
- 55 9. A light weight base for a disconnecting switch adapted to be mounted on a pole for opening the circuit between a pair of transmission line conductors comprising, in combination, a pair of spaced apart structural frame members, a bracket formed of plate-like material and secured between said frame members at each end to rigidly brace them relative to each other, each of said brackets including means for connection thereto of a strain insulator to each of which one of said conductors is fastened, and one of said 60 brackets being arranged and adapted to support
- an insulator, and an insulator support bracket rotatably mounted between said frame members intermediate the ends thereof.
10. A light weight base for a disconnecting switch adapted to be mounted on a pole for interconnecting a pair of transmission line conductors comprising, in combination, a pair of L-shaped spaced apart structural frame members with the outer surfaces of the upstanding legs facing toward each other, a bracket formed of 10 plate-like material and welded to the opposite faces of said frame members at each end to rigidly brace them relative to each other, each of said brackets including means for connection thereto of a strain insulator to each of which one of 15 said conductors is fastened and one of said brackets being arranged and adapted to support an insulator, a shaft extending transversely through said upstanding legs of said frame members intermediate their ends, a pair of inverted 20 L-shaped hinge members carried by said shaft between said upstanding legs, and an insulator support bracket carried by said hinge members having a generally rectangular opening for receiving a correspondingly shaped operating member.
11. A combined support bracket and yoke for a tilttable insulator of a disconnecting switch disposed to be rotatably mounted on a base comprising, in combination, a pair of interfitting generally U-shaped members formed of plate-like material in such manner as to form a generally rectangular opening for receiving a correspondingly shaped operating shaft, clamp means for 30 securing said operating shaft in said opening, and means for securing said insulator on the upper side of said members, the end of one of said members cooperating with said base to limit the movement of said insulator in one direction.
12. A combined support bracket and yoke for a 40 tilttable insulator of a disconnecting switch disposed to be rotatably mounted on a base comprising, in combination, a pair of interfitting generally U-shaped members formed of plate-like material in such manner as to form a generally 45 rectangular opening for receiving a correspondingly shaped operating shaft, a clamp plate in said opening, means extending from the upper side of said members into said opening and cooperating with said clamp plate to secure said operating shaft in position, and means extending into the upper side of said members for securing said insulator thereon, the ends of one of said members cooperating with said base to limit 50 the movement of said insulator toward the open and closed positions of said switch.
13. A shaft to which a torsional force is applied for simultaneously operating a plurality of widely spaced apart transmission line disconnecting switches or the like, comprising, in combination, a Z-shaped metal member formed of relatively thin plate-like material, and reinforcing means of zig-zag construction secured at spaced points to the web and one flange of said Z-shaped member for bracing it against the stress set up therein on application of said torsional force.
14. A shaft to which a torsional force is applied for simultaneously operating a plurality of widely spaced apart transmission line disconnecting switches or the like, comprising, in combination, a Z-shaped metal member formed of relatively thin plate-like material, and a pair of continuous reinforcing members of zig-zag construction welded at spaced points on opposite sides of the web of said Z-shaped member and to the adj- 75

cent flanges for bracing it against the stress set up therein on application of said torsional force.

15. A switch comprising, in combination, a switch blade having a longitudinally convex contact surface along one side and a small radius projection on the other side, and a cooperating contact assembly including a pair of contact members having contact surfaces facing in opposite directions, one of said contact surfaces being longitudinally convex for substantially point contact engagement with said longitudinally convex surface of said switch blade and the other being substantially plane for substantially point contact engagement with said small radius projection, said contact members being biased toward each other, and means limiting the movement of said contact members toward each other to position the contact surfaces thereof slightly within the path of relative movement of the contact surfaces of said switch blade.

16. A switch comprising, in combination, a pair of spaced apart switch blades each having on adjacent sides a longitudinally convex contact surface and on the other sides a small radius projection; and a cooperating contact assembly including a pair of biased apart contact fingers having longitudinally convex contact surfaces facing outwardly for substantially point contact engagement with the longitudinally convex surfaces of said switch blades, and a pair of plate-like contact members for substantially point contact engagement with the small radius projections on said switch blades.

17. A switch comprising, in combination, a pair

of relatively movable switch members, a first pair of spaced apart flexible contact fingers carried by one switch member each having a convex longitudinal contact surface, a pair of substantially inflexible contact fingers also carried by said one switch member and disposed adjacent said first pair of contact fingers, and a second pair of flexible spaced apart contact fingers carried by the other switch member each having convex contact surfaces on opposite sides for engagement on one side with the corresponding one of said first pair of contact fingers and on the other side with the corresponding one of said inflexible contact fingers.

18. A switch comprising, in combination, a pair of relatively movable switch members, a first pair of spaced apart flexible contact fingers carried by one switch member each having a convex longitudinal contact surface facing outwardly, a pair of substantially inflexible contact fingers also carried by said one switch member each being individual to one of said first pair of contact fingers and spaced outwardly from the contact surface thereof, means biasing said first pair of contact fingers apart, and a second pair of flexible spaced apart contact fingers carried by the other switch member each having convex contact surfaces on opposite sides for engagement on one side with the corresponding one of said first pair of contact fingers and on the other side with the corresponding one of said inflexible contact fingers.

ALLAN RAMSEY.
